L. H. BEAR.

AUTOMATIC GAS SAVING ATTACHMENT FOR GAS STOVES.

APPLICATION FILED NOV. 10, 1910.

1,090,094.

Patented Mar. 10, 1914

UNITED STATES PATENT OFFICE.

LEWIS H. BEAR, OF LOS ANGELES, CALIFORNIA, ASSIGNOR TO BEAR AUTOMATIC GAS STOVE CO., OF LOS ANGELES, CALIFORNIA, A CORPORATION OF CALIFORNIA.

AUTOMATIC GAS-SAVING ATTACHMENT FOR GAS-STOVES.

1,090,094.

Specification of Letters Patent. Patented Mar. 10, 1914.

Application filed November 10, 1910. Serial No. 591,709.

To all whom it may concern:

Be it known that I, LEWIS H. BEAR, a citizen of the United States, residing at Los Angeles, in the county of Los Angeles and State of California, have invented new and useful Improvements in Automatic Gas-Saving Attachments for Gas-Stoves, of which the following is a specification.

This invention is an improvement over 10 the attachment for gas stoves patented to me Feb. 23, 1904, by Letters Patent of the United States, No. 752749.

An object of this invention is to provide an automatic gas saving cut-off for gas 15 stoves which is inconspicuous as an attachment; in which the use of springs is dispensed with and the liability of getting out of adjustment is minimized; and in which the valve is practically frictionless and is 20 constructed to avoid the necessity of any stuffing box.

Further objects are cheapness of manufacture, ease of assembling the parts, and ease of installation in the stove.

25 The invention relates to the construction and arrangement of the valve head and valve, the means for operating the valve and the construction and arrangement of the stove frame and the means for mounting the 30 head and operative parts on the stove frame.

The accompanying drawings illustrate the invention.

Figure 1 is an elevation partly in section on line x^3-x^1 , Figs. 2 and 4, of a gas stove 35 provided with this invention as it appears when the pilot valve is open, the pilot pipe lighted, the cut-off valve closed and the main burner extinguished. Fig. 2 is a fragmental broken plan of the invention partly in section 40 on line x^2 , Figs. 1 and 4. Fig. 3 is a fragmental vertical section on line indicated by x^3-x^1 , Figs. 2 and 4. The cut-off valve being open. Fig. 4 is a broken fragmental front elevation partly in section on line 45 x^4-x^4 , Fig. 1. Fig. 5 is a fragmental sectional elevation from line x^5-x^5 , Fig. 1 looking toward the left. Fig. 6 is an enlarged fragmental detail, in elevation, of the joint between the upper limb and the link of the 50 compound lever that operates the cut-off valve. Fig. 7 is a perspective view of the bracket detached.

The stove frame 1 is provided in front and behind the burner opening 2 with notches 3, 4, to receive the front and rear 55 spider lugs 5, 6, that project laterally at the front and rear of the spider 7; there being a pair of front lugs 5 and a pair of rear lugs 6; the spider otherwise being of the same construction as those in common use in gas 60 stoves.

The notches 3 and 4 are cut into the inner upper corners of the frame 1. The front notches are open at the top and back and the rear notches are open mainly at the front; 65 the frame 1 being made of angle iron and the notches being cut into the corners as shown so that the front edge of the spider may be raised and lowered while the rear edge of the spider is pivotally supported by 70 the lugs in the rear notches 4 so that the spider is free and detached from the stove frame and other parts may be readily removed while the stove is being cleaned. By this construction of the spider and 75 frame, the spider is delicately pivoted so as to be easily moved by the weight of light aluminum cooking utensils as well as the heavier utensils. The ends of the lugs 5 and 6 are rounded on their upper sides to 80 allow the cooking utensil to be shoved on readily from the front and to allow the pivotal action at the rear without interference at the top of the angle iron frame under the top limb of which the rear limbs extend. 85

A bracket 8 is bolted to the front rail of the frame and a valve head or block 9 is fastened to the bracket by longitudinally perforated screw-threaded plugs 10 and 11 that have heads 12 and 13, that are inserted 90 through holes in said bracket and that are screwed into the head 9, which is provided with a bore 14 forming a vertical gas-way communicating with the bores of the plugs 10 and 11 and with the nipple 15 of the gas 95 supply pipe 16; said nipple 15 being controlled by the usual valve 17. The heads 12, 13, engage the front wall of the bracket 8 and hold the head 9 firmly in place against such front wall when the plugs are screwed 100 home.

The head 9 is provided with a screw-threaded orifice 18 into which is screwed the pilot light valve 19 that is a conical pointed

screw-threaded plug, the inner end of which is adapted to close the axial bore of the pilot light plug 10 into the head end of which is screwed the pilot light pipe 20. 5 The cut-off valve 21 slidably fits an enlarged portion 22 of the bore which forms the gas-way 14, and is provided with a reduced tip 23 the end of which is conical forming a valve face to fit a conical seat 24 10 to close the passage through such bore from the nipple 15 to the plug 11 which forms the jet piece or nozzle that discharges gas into the air mixer 25 which receives air through the orifices 26 in the front wall of 15 the bracket 8 said orifices controlled by the shutter 27 in the usual manner.

The bracket 8 is bent from a single piece of sheet metal and comprises the front wall 28, side arms 29 and ears 30 at the tops of 20 said side arms. The front wall is provided with holes 31, 32, through which the bodies of the plugs 10 and 11 insert. Said bodies are provided with cylindrical portions 33 next to their heads to fit the holes 31, 32, 25 and also to fit spacers 34, 35, which are arranged around said bodies outside the bracket to hold the bracket wall 28 and the valve block 9 spaced apart to receive between them the shutter 27 having the openings 36 and that turns on the spacer 35 which surrounds the main plug 11 that constitutes the nozzle for injecting gas into the air mixer 25 and discharging it through the usual pipe *a* to the usual gas burner *b* 30 centrally located below the tilting spider 7.

The front bar 37 of the spider rests upon the free end of the upper member 38 of a compound lever that is fulcrumed to the bracket arms 29 and consists of three U- 40 shape members 38, 39, 40. The upper and lower members 38 and 40 are fulcrumed by pins 41, 42, respectively, to the tops and bottoms of the bracket arms 29 which are provided with holes 43, 44, for that purpose.

45 The fulcrumed members 38 and 40 are connected by a link 39 that is pivoted thereto and constitutes the intermediate member of the compound lever. The compound levers provide valve-operating means beneath the top of the stove frame so as to be protected and not detract from the appearance of the stove.

The tips 45 of the lever member 38 are bent toward each other and are provided 55 on their top edges with notches 46 to engage slots 49 in the link 39, the lower end of which is pivoted by pin 50 to the weighted end of the lower lever member 40. By this construction of a compound lever, the lever 60 can be located behind the front wall 28 of the stove and can be arranged around the air mixer 25, thus making it adaptable to a gas stove of minimum height and furthermore the U-shaped members of the lever act

as lateral bracing and prevent lateral movement of the lever.

The weight 51 of the weighted lever 40 extends from arm to arm of the lever and is adjustable along the free arms of such lever; being clamped thereto by the clamp 70 bar 52 and set screw 53.

The front end of the lower weighted lever 40 is provided at its middle with a slot 54 to receive a flange 55 that is adjustably mounted by thumb nuts 56, 57, on the screw-threaded stem 58 of the cut-off valve 21. By this method of connecting the lever with the valve stem any tendency to bind is avoided and a very delicate adjustment of the valve may be made. Said stem extends 80 through a gland 59 that is screwed into the lower end of the valve head 9 and that is provided at its upper end with a valve seat 60 to fit the lower conical valve face 61. The advantage of this construction of the 85 valve and valve seats 21, 24, 60 permits of relative adjustment of the valve seats toward and from one another and for the removal of the valve so that the valve tip 23 and valve face 61 and also the valve seats 90 24, 60 can be readily re-ground.

As the lever member 40 moves on its fulcrum 42 it acts upon the flange 55 to move the valve up to cut off or tightly close the lower end of the gas-way 14 or down to open 95 communication between such way and the bore of the jet plug or nozzle 11. The gas mixer 25 is fastened by four screws 62 to the bracket and one or more of said screws may be arranged to clamp the shutter 27 in 100 set position. Bolts 63 passing through the top limb of the stove frame and through the ears 30 of the bracket fasten the bracket to the frame.

The weight 51 is normally adjusted in 105 such position that it will readily tilt the spider 7 into the position shown in solid lines in Fig. 1, care being taken that the leverage is only sufficient to readily raise the front end of the spider and will allow 110 it to descend whenever a cooking utensil is placed upon the spider.

The pilot light valve 19 is normally set to admit to the pilot pipe 20 the gas requisite to furnish the pilot light and when the 115 valve 17 is open the pilot light must be ignited. As soon as any utensil is placed upon the spider 7 above the burner *b* the rear end of the top lever member 38 will be depressed thereby raising the weight 51 120 and lowering the cut-off valve to open the passage to the bore of the nozzle 11; and the gas issuing from the burner *b* is then immediately ignited by the pilot light. When the utensil is removed from the spider 125 the cut-off valve operates to close the upper valve seat 24 so that no further gas will escape. The cut-off valve therefore operates

under the force of the weight 51 to cut off the gas at the seat 24 and operates under the weight of the cooking utensil to close the cut-off valve at the seat 60. Thus leakage 5 is always prevented without the use of any stuffing box.

The lower edges of the front wall of the bracket are provided with vertical slots 64 to accommodate the side arms of the 10 weighted lower lever 40.

The top of the valve head 9 is preferably rounded and the frame is provided with a rounded notch 65 into which it seats, thus adding to the stability of the head.

15 The spider is provided with vertical laterally projecting knife edges 66 below the spider supporting lugs to contact with the frame 1 to hold the spider in true position while it moves up and down, so as to avoid 20 excessive friction and binding between the frame and spider when the spider is moved up and down.

The lower fulcrumed lever 40 is brought into adjustable operative relation to the 25 valve by means of the adjustable flange 55 in the slot 54; and by moving the flange up or down on the valve stem, the upper lever member 38 will be made to lift the front edge of the spider to a greater or less height 30 as may be required to seat the valve in the gland exactly when the spider lugs seat on the frame. By turning the screw 53 to loosen the clamp-bar 52 the weight 51 may be shifted to give the delicacy of operation 35 required whereby moderate weight on the spider will open the valve and yet the valve will be firmly seated in its seat 24 when the spider is free.

The flange is preferably circular so that 40 it will always engage the slot though it is turned on the valve stem when the nuts are turned.

I claim:—

1. In a gas saving device, a valve head 45 provided with a gas-way; a nozzle communicating with the gas-way; a valve provided with two valve faces and a stem, one of said faces being adapted to close the valve-way; a gland screwed into the valve 50 head to form a seat for the other valve face; said stem extending through the gland; a flange adjustably locked on said stem, a lever provided with a slot to engage said flange and a tilting spider to operate the 55 lever.

2. In a gas saving device, the combination 60 with a tilting spider and a burner beneath the spider, of a valve head provided with a nozzle to supply the burner, a cut-off valve in the head and a compound lever comprising a fulcrumed member engaged by the spider, a fulcrumed member in operative relation to the valve, a link connecting the fulcrumed members and means to operate

the compound lever to close the valve and 65 tilt the spider all of said lever members being U-shaped.

3. The combination with a stove frame having notches in its upper inner corners, of a tilting spider provided at its edge with 70 lugs projecting laterally into the notches, a burner beneath the spider, means to supply fuel to the burner, a cut-off valve for the gas supply, and means between the cut-off valve and the tilting spider and operable by the spider to operate the valve. 75

4. In a gas stove, the combination with a stove frame having notches in its inner corners, of a tilting spider provided with lugs 80 to seat in said notches and vertical laterally projecting knife edges to contact the stove frame, a valve, and valve operating means between the tilting spider and the valve.

5. The combination with a stove frame; 85 of a bracket provided with a front wall, side arms normal to the front wall and ears at the top of the side arms secured to the stove frame; a valve head provided with a bore constituting a valve-way and a gas-way 90 and provided with a valve seat between the gas-way and valve-way; said head also being provided with a hole for a gas nipple, two holes for plugs and a hole for a pilot light valve; a gas nipple in said hole and 95 longitudinally bored plugs in said two holes; said longitudinally bored plugs being provided with heads and inserted through the bracket wall and screwed into the head a valve to close and open the bore in one of 100 the bored plugs; a valve to open and close the valve seat in the valve head; a lever pivoted to the bracket arms and operably connected with the valve; and a tilting spider mounted partly on the stove frame 105 and partly on the lever to operate the lever.

6. The combination with a valve head, of a valve a bracket provided with an air opening; a gas mixer fastened to the bracket to receive air through the opening; axially 110 bored headed plugs passed through the bracket wall and screwed into the valve head to hold the valve head and bracket together and to discharge gas through the bracket into and inside the air mixer; and a shutter 115 mounted concentric to one of said bored plugs to close the air opening.

7. The combination with a valve head, of a valve a bracket provided with air openings, a longitudinally bored headed plug inserted through the bracket and screwed into the valve head, a spacer around the plug to hold the valve head and the bracket apart, and a shutter journaled on the spacer to regulate the size of the air opening. 120

8. In a gas saving attachment for gas stoves having a tilting spider and a cut off valve, a compound lever arranged between

the spider and the valve and comprising three U-shape members; and two bracket arms between which two of such members are fulcrumed one above the other, the third member pivotally connecting said fulcrumed members.

In testimony whereof I have hereunto set

my hand at Los Angeles, California, this 3d day of November, 1910.

LEWIS H. BEAR.
